US00D999092S

(12) **United States Design Patent** (10) **Patent No.:** **US D999,092 S**
(45) **Date of Patent:** **** Sep. 19, 2023**

(54) **NECKLACE**

(71) Applicant: **Harry Winston SA**, Plan-les-Ouates (CH)

(72) Inventor: **Delphine Abdourahim**, New York, NY (US)

(73) Assignee: **Harry Winston SA**, Plan-les-Ouates (CH)

(**) Term: **15 Years**

(21) Appl. No.: **29/826,701**

(22) Filed: **Feb. 15, 2022**

(30) **Foreign Application Priority Data**

Aug. 20, 2021 (WO) WIPO107839

(51) **LOC (14) Cl.** **11-01**

(52) **U.S. Cl.**

USPC **D11/7**

(58) **Field of Classification Search**

USPC D11/6-8, 10, 11, 16

CPC A44C 15/00; A44C 15/005; A44C 25/001

See application file for complete search history.
